H. G. FERGUSON.
OUTLET DEVICE FOR GRAIN CARS,
APPLICATION FILED DEC. 6, 1920.

1,410,743.

Patented Mar. 28, 1922.

Inventor -

H. G. Ferguson
by Cook & McCauley Atty.

UNITED STATES PATENT OFFICE.

HENRY G. FERGUSON, OF HUTCHINSON, KANSAS.

OUTLET DEVICE FOR GRAIN CARS.

1,410,743.

Specification of Letters Patent. Patented Mar. 28, 1922.

Application filed December 6, 1920. Serial No. 428,558.

To all whom it may concern:

Be it known that I, HENRY G. FERGUSON, a citizen of the United States of America, and a resident of Hutchinson, in the county 5 of Reno and State of Kansas, have invented certain new and useful Improvements in Outlet Devices for Grain Cars, of which the following is a full, clear, and exact description, reference being had to the accompanying 10 drawings, forming a part of this specification.

This invention relates to improvements in outlet devices for grain cars, and more particularly to a device whereby grain may be 15 discharged through the floor of a grain car so as to relieve the grain pressure on the ordinary grain door, thus allowing the grain door to be readily removed, or otherwise opened, without mutilating or in any way 20 damaging the grain door.

Attempts have been made to devise a practical means for discharging grain through the floor of a car for the purpose of relieving the grain pressure on the ordinary vertical grain doors at the sides of the car, but so far as I am aware this has never been done in actual practice. The outlet device in the floor should not in any way interfere with the use of the car for other freight 25 30 35

in addition to grain; it should not form either a projection or depression in the floor of the car; it should be strong enough to withstand severe shocks which may be caused by the dropping of heavy objects onto the 40 device, and to completely solve this particular problem, the new device must not be in any way objectionable in an ordinary freight car.

My object is to produce an absolutely 45 practical grain outlet device of this kind meeting all of the service requirements and having no disadvantages which would prevent its use in an ordinary freight car.

Briefly stated, the new device comprises a 50 strong and simple metal door frame which lies flush with the floor of the car, a strong sliding door mounted in said metal door frame so as to also lie flush with the car floor, and a discharge spout leading from said door frame to the side of the car. The invention lies in the foregoing elements and in certain specific details of construction co-operating with each other to provide a simple solution of this particular problem.

Fig. I is a fragmentary vertical section 55 illustrating certain elements at one side of a freight car body equipped with my auxiliary outlet device.

Fig. II is a front elevation of the structure shown in Fig. I, the elements above the 60 car floor being omitted.

Fig. III is a section on the line III—III, Fig. I.

1 designates the side sill of a railway car, 65 2 the intermediate sill, and 3 the horizontal car floor resting on said sills. 4 designates one of the ordinary posts (Fig. I) which form the side walls of the doorway in the freight car, and 5 is an ordinary vertical grain door adapted to engage the inner face 70 of the door posts. This ordinary grain door 5 may be nailed to the door posts, or it may be slideable vertically. Although both of these types of grain doors 5 are well known in the art, it is customary to nail the grain door 75 to the door posts, instead of using the type which moves vertically along the door posts. However, in the use of either type of grain door, the door itself is subjected to the outward pressure of the grain in the car, and 80 considerable difficulty has been experienced in opening such doors. It is usual to cut an opening in the lower portion of the grain door for the purpose of permitting escape of the grain adjacent to the door, thereby 85 relieving the grain pressure and permitting free removal of the door.

The new device includes a frame, or guide member, A flush with the top face of the car floor, and a slideable door B mounted in the 90 frame A. The sliding door B is also flush with the horizontal top face of the car floor 3. A discharge opening 7 is formed in the car floor at a point directly below the door B, and this door B may be moved to the 95 right from the position shown in Fig. I, for the purpose of discharging grain into a spout S below the car floor.

The metal door frame A comprises a horizontal web 8 below the top of the floor, side 100 members 9 at opposite sides of the door B, and a rear member 10 at the rear of the door. These elements 8, 9 and 10, are integrally connected together, and they may be conveniently made of cast iron, or cast steel. 105 The side members 9 are provided with longitudinal grooves for the reception of flanges 11 which extend from the sides of the metal

door B, and the rear member 10 is provided with a groove for the reception of a flange 12 at the rear edge of the door, said grooves and flanges being below the horizontal top 5 face of the door. When the door occupies its closed position, the flanges 11 and 12 extend into the registering grooves in the door frame members 9 and 10, so as to prevent leakage of grain through the discharge opening 7. The door frame A is open at the side 10 of the car, so the door B can be moved to the right from the position shown in Fig. I, to allow the discharge of grain through the opening 7 in the car floor. The horizontal 15 web 8, forming part of the door frame, is provided with an opening which registers with the discharge opening 7 in the floor.

The top of the wooden floor 3 is recessed around the discharge opening 7 to receive 20 the door frame A which lies flush with the top of the floor. Screws 13 may be used to secure the door frame to the floor, as shown in Figs. I and III. These screws pass through flanges at the side and rear 25 margins of the door frame.

At the front of my auxiliary outlet device, portions of the floor 3, side sill 1 and siding 14 may be cut away to receive a locking device whereby the door may be secured 30 in its closed position to prevent accidental displacement thereof. A flange 15, extending downwardly from the front of the door frame, is provided at its lower end with a forwardly extending keeper 16, and a flange 35 17 which extends downwardly from the front end of the door is slotted at 19 to receive the keeper 16. As shown in Figs. I and II, the keeper 16 extends through slot 19 to receive the locking pin 18. This locking pin 18 is secured to the door by means 40 of a pin 20 extending through a slot in the locking pin. An ordinary car seal 21 may be applied to the lower end of locking pin 18 for the purpose of sealing the door B in 45 its closed position. In addition to locking the door B in its closed position when the freight car is used for the shipment of grain, the locking device just referred to also prevents accidental opening of the door B when 50 the freight car is used for other purposes.

To prevent removal of the door B, a stop member 22 extends downwardly from the rear portion of the door, and when this door is moved to its open position, the said stop 55 member engages an abutment 23 on the web 8, so as to limit the movement of the door.

The sectional spout S comprises a U-shaped sheet metal intake member 24, located 60 between the sills 1 and 2, and having outwardly turned top flanges 25 attached to the bottom of the floor 3 by means of nails, or other suitable attaching devices. Outwardly turned side flanges 26, extending 65 from the intake member 24, are secured to

the sills 1 and 2 respectively by means of nails, or the like, and a lower flange 27 is secured to the bottom of the intermediate sill 2. The bottom of the intake member 24 is inclined downwardly from the intermediate 70 sill 2 to a point below the side sill 1. 28 designates the U-shaped discharge member lapping the lower portion of intake member 24 to form a continuation thereof, said discharge member having outwardly turned top 75 flanges 29 attached to the bottom of the side sill. The grain passing through the discharge opening 7 drops onto the intake member 24 whereby it is conducted to the open discharge member 28 at the side of the car. 80

I claim:

1. A grain car provided with a floor having a discharge opening, a metal door-frame arranged in a horizontal position flush with the top of said floor, a horizontally movable 85 door slidably mounted in said door frame to close said discharge opening, the top of said door being directly above said opening and flush with said floor and door-frame and a locking device whereby said door is secured directly to said metal door-frame, said locking device comprising a keeper extending from the outer end of said door frame, a flange extending downwardly from the outer end of said door to receive said keeper, 95 and a locking pin carried by said flange and adapted to enter said keeper.

2. A grain car provided with a floor having a discharge opening, a metal door frame comprising a horizontal web below the top 100 but above the bottom of said floor and marginal guide members flush with the top of the floor, said web being integral with said marginal guide members and provided with an opening registering with said discharge 105 opening, said metal door frame being thinner than said floor, and the top of said floor being recessed to receive said frame, a horizontal door mounted above said web and having marginal side flanges which extend 110 into said guide members, the top of said door being flush with the top of said door frame and also with said floor, said door frame being open at the side of the car to permit horizontal movement of said door, and a discharge spout leading from said openings. 115

3. A grain car provided with side and intermediate sills, a floor on said sills, a sectional discharge spout comprising a U-shaped sheet metal intake member located 120 between said sills and having outwardly turned top flanges attached to said floor and outwardly turned side flanges attached to the respective sills, the bottom of said intake member being inclined downwardly 125 from said intermediate sill to a point below said side sill, and a U-shaped discharge member lapping said intake member to form a continuation thereof, said discharge member having outwardly turned top flanges 130

attached to said side sill, a metal door frame comprising a horizontal web below the top of said floor and marginal guide members flush with the top of the floor, said web and 5 floor being provided with registering discharge openings, and a horizontal door mounted above said web and having marginal flanges which extend into said guide members, the top of said door being flush with the top of said door frame and also 10 with said floor.

In testimony that I claim the foregoing I hereunto affix my signature.

HENRY G. FERGUSON.
